United States Patent Office

Des. 231,220
Patented Apr. 9, 1974

231,220

BUILDING

Armand V. Ruocco, Trooper, Pa., assignor to The Rustler,
Inc., King of Prussia, Pa.

Filed Mar. 26, 1973, Ser. No. 345,038

Term of patent 14 years

Int. Cl. D25—03

U.S. Cl. D13—1 B

FIG. 1

FIG. 2

FIG. 1 is a front elevation view of a building in accordance with the present invention;

FIG. 2 is a rear view thereof and is shown in a reduced scale being 60% of FIG. 1;

FIG. 3 is a left side elevation view thereof and is shown in a reduced scale being 60% of FIG. 1; and

FIG. 4 is a top plan view thereof and is shown in a reduced scale being 65% of FIG. 3.

The undisclosed right side is a mirror image of its respective left side elevation view.

I claim:

The ornamental design for a building, substantially as shown and described.
